SHUTTLE EYE

Antonio Villani, Milford, Mass., assignor to
Draper Corporation, Hopedale, Mass., a corpora-
tion of Maine

Application February 28, 1945, Serial No. 580,090

6 Claims. (Cl. 139—223)

The present invention relates generally to loom shuttles and, as illustrated herein, relates more particularly to means for preventing unthreading of such shuttles.

Automatically threading loom shuttles are usually provided with a threading block having a longitudinal thread passage, a side delivery eye and a transverse passage connecting the longitudinal thread passage and the side delivery eye. During the first pick after a new filling carrying bobbin has been transferred to the shuttle, the shuttle is partially threaded and the filling thread is in the longitudinal thread passage. During the next or return pick the shuttle is completely threaded and the filling thread runs from the longitudinal thread passage, through the transverse passage and into the side delivery eye. Under some conditions, the filling thread may be thrown upwardly out of the side delivery eye and the shuttle will unthread either partially or completely. Various constructions have been proposed heretofore but have either interfered substantially with the threading of the shuttle or have been easily damaged during operation of the loom.

One object of the present invention is to provide a threading block by the use of which the above mentioned difficulties will be overcome. To this end and in accordance with one feature of the invention, the usual threading block is provided at the side delivery eye with a trap member which is supported by the block and has portions against which the filling runs during picking of the shuttle, one end of the trap member is so located within a recess formed in the threading block that the filling thread readily enters the side delivery eye but is prevented from moving upwardly out of the side delivery eye.

Another object of the invention is to improve generally upon the construction and operation of shuttles and threading blocks therefor.

With the above and other objects and features in view, the invention will now be described with particular reference to the accompanying drawings in which:

Fig. 1 is a plan view of a portion of a shuttle in which the present invention is embodied;

Fig. 2 is a view in front elevation of the shuttle shown in Fig. 1;

Fig. 3 is a view in section taken along the line III—III of Fig. 1;

Fig. 4 is an enlarged detail view, partly in section, showing the filling trap in position; and

Fig. 5 is a detail view, partly in section, showing the side delivery eye and trap in front elevation.

The present invention is illustrated as embodied in a usual type of automatically threading shuttle 10 in which a filling carrier or bobbin 12 is automatically replaced when the filling thereon is substantially exhausted. The shuttle 10 is provided with a recess 16 in which the bobbin 12 is removably supported and a cavity 18 communicates therewith and in which a usual threading block 20 is mounted and secured in position by a bolt 22.

The threading block 20 is provided with a usual longitudinal thread passage 24 having a pair of tension pads 26 adjacent to the inner end thereof. The block 20 is provided with an outwardly and rearwardly projecting hook 28 which terminates in a groove or recess 30 formed in the shuttle body. The threading block 20 is also provided with a downwardly extending horn 32 beneath which the filling thread passes to the side delivery eye 34.

The side delivery eye 34 is provided with a thread trap member 36 which is arranged to permit the filling to enter the side delivery eye 34. The member 36 is preferably formed of relatively heavy and stiff steel wire which is preferably coated with a metal such, for example, as chromium to provide a hard wear resisting surface. The wire is bent into a generally rectangular shape, as shown best in Figs. 4 and 5. The trap 36 is provided with a substantially vertical leg 38, the upper end portion of which is inserted in a hole 40 formed in the threading block 20. This vertical leg 38 takes the place of one of the usual hardened posts against which the filling bears when the shuttle is picked in one direction. The wire is then bent outwardly and forms a substantially horizontal leg 42 which fits into a recess 44 formed in the body of the shuttle 10 and which extends across the bottom of the side delivery eye 34. The wire is then bent upwardly to form a substantially vertical leg 46 which is substantially parallel to the leg 38 and which fits into a substantially vertical recess formed in the outer wall of the side delivery eye 34. The wire is further bent inwardly, downwardly and slightly rearwardly to form an inclined leg 48 which terminates in a recess 50 formed in the threading block 20. The trap member 36 at the junction between the vertical leg 46 and the inclined leg 48 is provided with a projection 52 which is designed to prevent the filling thread from being caught between the trap and the wood of the shuttle.

When the shuttle 10 is picked out the right hand shuttle box after an exhausted bobbin has

been replaced by a full bobbin, the filling thread passes between the tension pads 26 and extends into and through the longitudinal thread passage 24 of the threading block 20 and under the hook 28. During the next, or return, pick the filling passes down under the horn 32 and is pulled inwardly over the inclined leg 48 and into the side delivery eye 34. The free end of the leg 48 extends into the recess 50 a distance sufficient to prevent the thread from being thrown upwardly and out of the eye during subsequent picks but does not interfere appreciably with the threading operation. The trap member 36 performs another necessary and desirable function in that the vertical legs 38 and 46 form posts over which the filling runs during operation of the shuttle.

Having thus described my invention, what I claim as new and desire to secure by Letters Patent of the United States is:

1. An automatically threading loom shuttle comprising a shuttle body having a threading block and a side delivery eye, said block having a longitudinal thread passage and a transverse thread passage communicating with said side delivery eye, and a trap member shaped to provide a pair of substantially vertical posts at opposite sides of the delivery eye, and a portion projecting from the upper end of one of the said posts toward the other post across the top of said side delivery eye and having a free end portion terminating under a portion of said threading block to form a thread trap.

2. In an automatically threading loom shuttle comprising a shuttle body having a threading block and a side delivery eye, said threading block having a longitudinal thread passage and a transverse thread passage communicating with said side delivery eye, and a trap member for said side delivery eye, said trap member having substantially parallel posts at each end of the side delivery eye, one of said posts having a portion extending across the top of said side delivery eye and having a free end portion extending under a portion of said threading block to permit the filling thread to enter said side delivery eye but preventing said filling thread from thereafter moving upwardly out of said side delivery eye.

3. An automatically threading loom shuttle comprising a shuttle body having a threading block and a side delivery eye, said threading block having a longitudinal thread passage and a transverse thread passage communicating with said side delivery eye, and a trap member for said side delivery eye supported by said block and said shuttle body, said trap member comprising a substantially vertical leg having a portion extending into said threading block and supported thereby, a substantial horizontal portion extending across the bottom of said side delivery eye, a substantially vertical leg parallel to said first leg, and a portion extending from said second leg downwardly toward the first mentioned leg

and having a free end portion terminating under a portion of said threading block.

4. In an automatically threading loom shuttle comprising a shuttle body having a threading block and a side delivery eye, said threading block having a longitudinal thread passage and a transverse thread passage communicating with said side delivery eye, said trap member being formed of a single piece of abrasion resisting material and comprising a pair of spaced substantially parallel posts at either side of the side delivery eye and connected at their lower ends by a bar extending across the bottom of said side delivery eye, one of said posts having a portion projected inwardly and downwardly across the top of said side delivery eye and having its free end portion terminating below a portion of said side delivery eye to form a thread trap.

5. In an automatically threading loom shuttle comprising a shuttle body having a threading block and a side delivery eye, said threading block having a longitudinal thread passage and a transverse thread passage communicating with said side delivery eye, said trap member being formed of a single piece of abrasion resisting material and comprising a pair of spaced substantially parallel posts at either side of the side delivery eye and connected at their lower ends by a bar extending across the bottom of said side delivery eye, one of said posts having a portion projected inwardly and downwardly across the top of said side delivery eye and having its free end portion terminating below a portion of said side delivery eye to form a thread trap, the other of said posts being inserted in a substantially vertical hole formed in said threading block to hold said thread member in position.

6. In an automatically threading loom shuttle comprising a shuttle body having a threading block and a side delivery eye, said threading block having a longitudinal thread passage and a transverse thread passage communicating with said side delivery eye, said trap member being formed of a single piece of abrasion resisting material and comprising a pair of spaced substantially parallel posts at either side of the side delivery eye and connected at their lower ends by a bar extending across the bottom of said side delivery eye, one of said posts having a portion projected inwardly and downwardly across the top of said side delivery eye and having its free end portion terminating below a portion of said side delivery eye to form a thread trap, the other of said posts being inserted in a substantially vertical hole formed in said threading block to hold said thread member in position, the bottom bar and the post having the inwardly and downwardly projecting portion being mounted in recesses formed in the shuttle body to prevent angular movement of the trap member when the threading block is secured in the shuttle.

ANTONIO VILLANI.
